(57) **CLAIM**

The ornamental design for a hydraulic bearing puller, as shown and described.

DESCRIPTION

FIG. 1 is a perspective view of a hydraulic bearing puller depicting an embodiment of a new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken line portion of the drawings is included to show unclaimed subject matter only and forms no part of the claimed design. The bottom of the depicted new design is flat and contains no surface ornamentation.
